UNITED STATES PATENT OFFICE.

CHARLES M. LUNGEN, OF BAYONNE, NEW JERSEY, ASSIGNOR TO SAFETY CAR HEATING & LIGHTING COMPANY, A CORPORATION OF NEW JERSEY.

INCANDESCENT-MANTLE LAMP.

968,375.

Specification of Letters Patent. Patented Aug. 23, 1910.

Application filed October 26, 1907. Serial No. 399,388.

To all whom it may concern:

Be it known that I, CHARLES M. LUNGEN, residing at Bayonne, in the county of Hudson and State of New Jersey, have 5 invented certain new and useful Improvements in Incandescent-Mantle Lamps, of which the following is a full, clear, and exact description, such as will enable others skilled in the art to which it appertains to 10 make and use the same.

This invention relates broadly to illuminating apparatus, but inasmuch as certain advantages characteristic of the invention prominently appear when it is resorted to 15 in gas lighting apparatus of the inverted type, it will be conducive to clearness to disclose it through one or more of its embodiments in such relation.

This invention has in view among other 20 objects the provision of an illuminating apparatus employing mantles in which the burner is so constructed as to enable access to be had to the gas nipple of the inspirator without removing the mantle from the end 25 of the burner tube and thus subjecting the fragile mantle to possible fracture.

Another object within the contemplation 30 of this invention is to so construct the apparatus as to enable the globe and reflector to be easily swung away from the mantle for purposes of polishing and renewal without endangering the mantle by accidental 35 contact with the hands and implements of the operator.

35 This invention in general seeks to provide a gas lighting apparatus which, from an operative standpoint, will in practical usage possess a high degree of efficiency and durability and which, structurally considered,

40 will be of the greatest possible simplicity commensurate with the ends attained and will be composed of but few parts all of which are capable of being manufactured at a minimum of cost and so correlated as to be 45 capable of being very readily assembled by the usual skill of the art to accomplish the purposes intended.

Other objects and advantages will be in 50 part obvious from the annexed drawings and in part pointed out in the following description.

The invention accordingly consists in the features of construction, combinations of

elements and arrangement of parts which will be exemplified in the construction hereinafter set forth, and the scope of the application of which will be indicated in the following claims.

In order that this invention may be the more fully understood and made comprehensible to others skilled in its relating arts, drawings illustrating several of the many possible utilizations of the same are appended as a part of this disclosure and, while the controlling features and principles of this 60 invention may be otherwise carried out by modifications falling within the intended scope of the claims, the herein disclosed embodiments are those which will ordinarily be resorted to in practice, and are regarded 70 as representing substantial improvements over many of the seeming equivalents thereof.

In the appended drawings, corresponding parts are similarly referred to by like characters of reference throughout all the figures of which—

Figure 1 is a vertical section of an illuminating apparatus embodying this invention wherein the various parts are shown in their 80 normal relationship. Fig. 2 is a sectional elevation of certain of the parts shown in Fig. 1 wherein the hinged mantle supporting frame has been swung about its pivot to enable access to the gas nipple of the inspirator, and wherein the double hinged bezel has been swung away from the mantle, 85 thus indicating the manner in which it is possible to clean the glassware and reflector carried by the bezel without coming in close 90 proximity to or otherwise endangering the mantle.

Continuing now with a more detailed description of the herein-disclosed embodiments of this invention, with such occasional reference to the drawings as may facilitate an understanding of the same, 1 denotes a bracket or other member forming a part of the gas lighting apparatus which is attached to the supporting wall or ceiling 100 by means of tie bolts 2 and 3, one or more of which may be utilized as a conduit for the gas consumed by the burner. In this embodiment, the bracket 1 has secured thereto a two part ring 4 which in turn clamps the 105 chimney member 5. This chimney member

is fashioned somewhat in the shape of a funnel; that is to say, it converges from the ring 4 and ends in a rising cylindrical draft tube portion 6. Preferably, the member 5 will be provided in its flaring portion with a series of air vents 7 and its discharge end may also carry a hood 8 suitable for regulating the flow of the rising products of combustion.

10 The above described parts may be enclosed in co-operative relation with the ventilator generally designated by 9 which may either be of the herein-disclosed structure or otherwise shaped as preferred.

15 The burner, in this embodiment, is shown mounted underlying the lower part of the draft tube 6 and comprises a body portion 10 having one or more escape channels 11 (indicated in dotted lines) and providing a

20 gas conduit 12 leading to a dust collection chamber 13. This body portion 10 may be utilized as a supporting member and to that end it may conveniently be attached to the draft tube, as shown, by means of screws 40

25 taking through the draft tube into the body portion. The chamber 13 is formed in the depending hub portion 14 which is in adjustable screw threaded connection with the interfitting section 15 which provides a re-

30 stricted bore 16 from which rises the dust collector 17. This collector 17 consists of a tube closed at its upper end and having a series of downwardly tending escape slots arranged in its periphery. The lower end

35 of the restricted bore 16 of the interfitting member 15 is provided with an adjustable gas nipple 18 which has a fine bore serving to project the gas across one or more air inlets provided by the section 19. This sec-

40 tion 19 is provided with a vertical channel 20 for the passage of the combustible mixture and the delivery edge of this channel is made to assume the form of a raised rim 21. Hinged to the member 19 is a mantle sup-

45 porting member 22 which carries a depending burner tube 23 serving to detachably receive the mantle support 24 to which is attached the mantle 25. The member 22 is provided with a recess complementary to

50 the raised rim 21 so that a tight union may be formed when the mantle supporting member 22 is retained against the member 19 by means of the spring catch 26. It will be perceived that, by virtue of this construc-

55 tion of the burner, the mantle permits of being readily swung to one side, thus enabling access to the nipple 18 for purposes of adjustment, repair or replacement. This having been done, the mantle supporting

60 frame may be swung back and clasped in tight union with the member 19.

The globe supporting means preferably comprises a two part hinged bezel. Thus in the construction shown, the annular member

27 is by means of hinge 28 pivoted to the 65 supporting portion 4, thus enabling such annular member to be swung downwardly away from the mantle as shown more clearly by Fig. 2. Preferably, an annular reflector plate 29 is carried by such annular member 70 27 so that the reflector may be more readily cleaned when the said member has been swung away from the main portions of the apparatus. A latch 30 of any approved construction suffices to retain the annular portion 27 in operative relation to the overlying parts of the apparatus. The globe itself is here shown to be mounted directly on an auxiliary supporting ring 31 which is in turn pivoted at 32 to the annular member 27 80 and is thus capable of being dropped down and away from the same as shown by Fig. 2. Normally, the ring 31 will be retained in interfitting relation with the member 27 by means of a latch 33. This ring 31 is adapted to provide a satisfactory mounting for the globe 34 and to that end it is provided with an annular groove 35 within which is seated an annular resilient ring or packing 36 which may be of asbestos. A spring ring 37 is secured to the annular ring 31 by means of screws and lugs 38 as will be understood. This invention contemplates the use of either a closed globe such as that shown by Fig. 2 or an open globe as shown by Fig. 1. 95

It will thus be seen that I have succeeded in devising an apparatus admirably adapted to attain the several ends of my invention. Under normal circumstances the apparatus will be found to be very compact as 100 to space and of a comparatively inexpensive construction. Its use does not involve any complexity of manipulation and the various parts requiring attention are peculiarly accessible without involving any undue liability as to breakage of the more delicate parts such as the mantle and the glass globe. Thus, if it be desired to repolish the globe, it may be swung into the position shown by Fig. 2 in which it is at once accessible in all 110 its parts and thus capable of being very easily and yet thoroughly cleaned. At the same time the reflector 29 may also be burnished without difficulty and if desired the mantle may be swung away also in the position shown by Fig. 2. This enables the operator to gain access to the gas nipple 18 for the purpose of adjusting the same.

As many changes could be made in the above construction and many apparently 120 widely different embodiments of this invention could be made without departing from the scope thereof, it is intended that all matter contained in the above description or shown in the accompanying drawings shall 125 be interpreted as illustrative and not in a limiting sense.

Having described my invention what I

claim as new and desire to secure by Letters Patent is:

1. An illuminating apparatus comprising in combination, a light emitting device, a member mounted adjacent said device and adapted to be swung away from said device, and a globe carried by said member and normally inclosing said device, said globe being mounted to swing away from said member.

2. An illuminating apparatus comprising in combination, a light emitting device, a member normally arranged adjacent to said device and adapted to be moved away from the same, and a globe carried by said member and adapted to be moved relatively to the same independently of the position of said member.

3. An illuminating apparatus comprising in combination, a light emitting device, a member pivotally mounted adjacent the same to enable it to be swung away from said device, and a globe holder carried by said member and adapted to be moved relatively to the same.

4. An illuminating apparatus comprising in combination, a light emitting device, a member pivotally mounted adjacent the same, and a globe holder pivotally mounted on said member.

5. An illuminating apparatus comprising in combination, a light emitting device, an annular ring pivotally mounted adjacent said device, and a globe holder carried by said ring and pivoted thereto at a point opposite the first mentioned pivot of said ring.

6. An illuminating apparatus comprising in combination, a light emitting device, a member mounted adjacent said device and adapted to be swung away from said device, a globe holder mounted in movable relation on said member, and a globe carried by said holder and normally inclosing said device.

45 7. An illuminating apparatus comprising in combination, a light emitting device, a member mounted adjacent to said device, and adapted to be moved away from the same, a latch for maintaining said member in normal position, a globe holder carried by said member and adapted to be moved relatively to the same independently of its position, and a globe carried by said holder and normally inclosing said device.

55 8. An illuminating apparatus comprising in combination, a light emitting device, a member pivotally mounted adjacent the same to enable it to be swung away from said device, a latch normally maintaining said member closely adjacent said device, a globe holder carried by said member and adapted to be moved relatively to the same, and a globe carried by said holder.

9. An illuminating apparatus comprising

in combination, a light emitting device, a member pivotally mounted adjacent the same, a globe holder pivotally mounted on said member to enable it to be swung away from the same, a latch for maintaining said holder in normal relation to said member, and a globe carried by said holder.

10. An illuminating apparatus comprising in combination, a light emitting device, an annular ring pivotally mounted adjacent said device, a latch for maintaining said ring in normal relation to said device, a globe holder pivoted to said ring at a point distant from the first mentioned pivot of said ring, and a globe carried by said holder.

11. An illuminating apparatus comprising in combination, a light emitting device, a member mounted adjacent said device adapted to be swung away therefrom, a reflector carried by said device, and a globe carried by said member and normally inclosing said device said globe being mounted to swing away from said member.

12. An illuminating apparatus comprising in combination, a light emitting device, a member normally arranged adjacent to said device and adapted to be moved away from the same, a reflector carried by said member, and a globe carried by said member and adapted to be moved relatively to the same independently of its position.

13. An illuminating apparatus comprising in combination, a light emitting device, a member pivotally mounted adjacent the same to enable it to be swung away from said device, a reflector carried by said member, and a globe holder carried by said member and adapted to be moved relatively to the same.

14. An illuminating apparatus comprising in combination, a light emitting device, a member pivotally mounted adjacent the same, a reflector carried by said member, and a globe holder pivotally mounted on said member.

15. An illuminating apparatus comprising in combination, a light emitting device, an annular ring pivotally mounted adjacent said device, an annular reflector carried by said ring and arranged to normally circumscribe said device and a globe holder carried by said ring and pivoted thereto at a point opposite the first mentioned pivot of said ring.

16. An illuminating apparatus comprising in combination, a light emitting device, a member pivotally mounted adjacent said device, a globe holder pivotally mounted upon said member, said globe holder having an annular globe supporting ledge, resilient packing seated on said ledge, a globe having a rim engaging with said packing, and a resilient globe retainer secured to said holder and bearing against the portion of said

globe opposite to said packing, said retainer having the form of an annular dished ring.

17. An illuminating apparatus comprising, in combination, a light-emitting device, 5 a member mounted adjacent said device and adapted to be swung away therefrom, a globe-holder mounted upon and in movable relation to said member, a globe carried by said holder and normally inclosing said device, 10 resilient packing interposed between

said globe and said holder, and a resilient retaining ring normally maintaining said globe on said holder and detachably secured to the latter.

In testimony whereof I affix my signature, 15 in the presence of two witnesses.

CHARLES M. LUNGREN.
